UNITED STATES PATENT OFFICE.

WILLIAM J. RANDOLPH, JR., OF NEWTON, IOWA.

COUPLING FOR THRESHING-MACHINES, &c.

SPECIFICATION forming part of Letters Patent No. 752,800, dated February 16, 1904.

Application filed May 12, 1903. Serial No. 156,839. (No model.)

To all whom it may concern:

Be it known that I, WILLIAM J. RANDOLPH, Jr., a citizen of the United States, residing at Newton, in the county of Jasper and State of Iowa, have invented a new and useful Improvement in Couplings for Threshing-Machines, &c., of which the following is a specification.

My invention relates to couplers, and is especially directed to a device of this character designed for use in connection with threshing-machines, but which may be employed for coupling cars or the like, and has for its objects to produce a device of this character which will be simple of construction, efficient in operation, one in which the coupling-jaws will automatically move into coupling engagement, and one in which the jaw-holding lever may be readily manipulated for releasing the jaws.

To these ends the invention comprises the novel details of construction and combination of parts more fully hereinafter described.

In the accompanying drawings, Figure 1 is a top sectional plan of a coupler embodying my invention in its preferred form, the parts being shown in coupled position. Fig. 2 is a similar view showing the parts in uncoupled position. Fig. 3 is a similar view showing an intermediate position of the parts. Fig. 4 is a longitudinal section. Fig. 5 is a top sectional plan of a modified form of the device, the parts being shown in coupled position. Fig. 6 is a similar view showing the parts uncoupled, the movement of the secondary jaw being shown in dotted lines.

Referring to the drawings, 1 indicates the platform of a traction-engine or the like, and 2 a portion of the tender or other vehicle which is coupled thereto. These parts are conventionally shown for the purpose of illustrating the operation of the coupler which constitutes the essence of my invention.

In practicing my invention I pivot to the platform or like part 1 by means a bolt 3 the draw-head 4 of my improved coupler, which is normally held against swinging movement by means of a draw-bolt 5, and on the tender or like part 2 I mount a suitable member 6,

carrying a pin 7, with which the jaws of my improved coupler engage when the parts are in coupled position, as shown in Fig. 1.

The draw-head 4 of my coupler consists of a top plate 8 and a bottom plate 9, which are disposed in vertical alinement and are spaced one from the other by front blocks 10, rear blocks 11, and an intermediate side block 12. The top and bottom plates of the draw-head are each recessed from its outer end inward, as at 13, said recess forming a guide which terminates in a substantially circular opening 14, which in practice receives the pin 7 when the parts are in coupled position.

15 indicates the primary coupling-jaw, which is mounted between the top and bottom plates of the draw-head and pivoted upon a vertical transverse pin 16. Said jaw is provided with a coupling knuckle or finger 17, which in practice extends across the guide-recess 13 in advance of the pin-receiving opening 14 to prevent escape of the pin, the end of the jaw 15 in advance of the finger 17 being beveled or inclined, as at 18, to constitute an outer beveled face for the finger 17. The jaw is further provided with a lateral inwardly-extending finger 19, which normally lies in rear of the pin-receiving opening 14 in position to be acted upon by the incoming pin for throwing the jaw 15 into its coupling position, as will be more fully hereinafter explained. The upper face of the jaw 15 is recessed, as at 20, above the finger 19, thus forming upon the inner edge of the jaw an inclined stop 21, and the jaw is further provided at its inner end with a rearwardly-extending finger 22, the purpose of all of which parts will presently appear.

23 indicates the secondary coöperating jaw, which is mounted between the top and bottom plates of the draw-head and is pivoted upon a pin 24, said jaw being provided with an inwardly-extending finger 25, having a front beveled or inclined face 26, the finger 25 being arranged to overlie the finger 19 and to extend within the recess 20 and have its inner end bear upon the inclined stop 21 of the primary jaw. The jaw 23 has its lower face

recessed, as at 27, to form a stop 28, with which the outer end of the finger 19 contacts when the parts are uncoupled to prevent accidental coupling engagement of the jaws.

5 29 indicates a lever mounted between the top and bottom plates of the draw-head transversely thereof and pivoted upon a pin 30, said lever being provided adjacent to one end with a notch or recess forming a shoulder 31 10 for engaging the finger 22 of the jaw 15 to maintain the parts in coupled position, as shown in Fig. 1. In this connection it is to be noted that when the jaw swings to coupling position the block 12 constitutes a stop 15 with which the finger 22 contacts to check it at proper position for engagement by the shoulder 31 of the lever, and that when the jaw is released and swung outward the block 12 serves as a stop to prevent the forward end 20 of the jaw swinging laterally beyond the head.

32 is a spring coiled upon the pin 30 and having a spring-arm 33, which normally holds the lever in engaging position, and with a second arm 34, which engages the secondary jaw 23 for maintaining the same in such position that the stop 28 will normally lie in the path of the finger 19.

35 is an operating member which extends forwardly from the lever 29, and 36 is a similar member extending rearwardly from the lever. These operating members are preferably in the form of ropes, which are attached to the lever at opposite ends thereof, and a pull upon either of which serves to release the lever from engagement with the jaw 15 to permit the latter to swing to uncoupling position.

In practice, supposing the parts to be in the position shown in Fig. 1, a pull upon either of the lever-operating members releases the 40 jaw 15 and permits the same to move to the position shown in Fig. 2 for releasing the pin 7. With the parts shown in the position as in Fig. 2 if the pin 7 is brought into coupling 45 position it first strikes the finger 19 and swings the jaw 15 inward, then contacts with the inclined outer face of finger 25 and moves the jaw 23 outwardly sufficiently to permit the outer end of finger 19 to pass the stop 28, when the finger 22 will contact with stop 12, 50 and the lever 29 will move automatically into engagement. If the parts occupy the position shown in Fig. 3, the pin 7 in passing to the coupled position will first contact with the outer beveled face of finger 17 and swing the 55 jaw 15 outward to permit the pin to pass the finger, then will next contact with finger 19 for swinging the jaw inward and with the beveled face of finger 25 for the purpose just explained.

60 In the modification shown in Figs. 5 and 6 the primary jaw 15^a is normally locked in coupling position by means of a lever 29^a, which has an integral forwardly-extending portion

shouldered, as at 31^a, for engagement with the finger 19^a of the jaw 15^a, the forwardly-extending portion of the lever 29^a being formed in advance of the shoulder 31^a into the secondary jaw 23^a, said jaw being provided with an inwardly-extending finger 25^a, which cooperates with finger 17^a, formed upon the primary jaw, for maintaining the pin 7^a within the opening 14^a, it being noted in this connection that the finger 17^a has a front beveled portion 18^a and finger 25^a a beveled portion 26^a, through the medium of which beveled portions the incoming pin automatically opens the jaws to permit its passage behind said finger and into the pin-receiving opening, the pin in practice acting first through the beveled face 26^a to move the jaw 23^a outward and release the finger 19^a from engagement with the shoulder of the lever 29^a and after passing the outer fingers contacts with the finger 19^a for swinging the primary jaw inward to coupling position and engaging the end of the finger with the shoulder. The lever 29^a is actuated for releasing the primary jaw by means of operating members 35^a 36^a and is moved automatically into position for engaging the primary jaw by means of a spring 32^a.

From the foregoing it will be seen that I produce a simple and efficient coupler which is admirably adapted for the attainment of the ends in view; but I do not limit or confine myself to the precise details herein shown and described, inasmuch as minor changes may be made therein without departing from the spirit or scope of my invention.

Having thus described my invention, what I claim is—

1. A coupler comprising a draw-head recessed to form a guide, said guide terminating in a pin-receiving opening, a pivoted jaw having a coupling-finger for closing the guide in advance of the opening, the walls of the recess cooperating with the finger for maintaining the pin, a finger extending in rear of the opening, a pivoted lever shouldered for engagement with the pivoted jaw, means for moving the lever automatically to engaging position, and means for operating the lever to release the jaw.

2. A coupler comprising a draw-head, a pivoted primary jaw, a pivoted secondary jaw coacting with the primary jaw to maintain the latter in uncoupled position, a pivoted lever shouldered for engagement with the primary jaw to maintain the same in coupling position, means for automatically moving the lever to engaging position, and means for operating the lever to release the jaw.

3. A coupler comprising a draw-head, a pivoted primary jaw provided with a coupling-finger, a pivoted secondary cooperating jaw provided with a stop, a finger associated with the primary jaw and engaging said stop

to prevent accidental coupling of the jaws, a pivoted lever shouldered for engagement with the primary jaw, means for moving the lever automatically to engaging position, and means 5 for operating the lever to release the jaw.

4. A coupler comprising a draw-head, a pivoted primary jaw, a pivoted secondary co-operating jaw, a pivoted lever shouldered for engagement with the primary jaw to maintain 10 the same in coupling position, a spring for moving the lever automatically to engaging position, and a pair of operating members

connected one with each end of the lever and extending therefrom in opposite directions and either operable for actuating the lever to 15 release the jaw.

In testimony that I claim the foregoing as my own I have hereto affixed my signature in the presence of two witnesses.

WILLIAM J. RANDOLPH, JR.
